UNITED STATES PATENT OFFICE.

MERRITT L. EMRICH, OF LOUISVILLE, KENTUCKY, ASSIGNOR TO UNITED STATES FOIL COMPANY, OF LOUISVILLE, KENTUCKY, A CORPORATION OF DELAWARE.

DESIGN FOR A DISPLAY CARD.

Application filed April 16, 1925. Serial No. 13,148. Term of patent 14 years.

To all whom it may concern:

Be it known that I, MERRITT L. EMRICH, a citizen of the United States, residing at 611 Weisinger Gaulbert Apts., Louisville, in the county of Jefferson and State of Kentucky, have invented a new, original, and ornamental Design for Display Card, of which the following is a specification, reference being had to the accompanying drawing, forming part thereof.

I claim:

The ornamental design for a display card, as shown.

MERRITT L. EMRICH.
